CLAIM

The ornamental design for a cheese slicer, as shown and described.

DESCRIPTION

FIG. 1 is a top perspective view of a cheese slicer showing my new design.

FIG. 2 is a left side and/or right side view thereof.

FIG. 3 is a top view thereof.

FIG. 4 is a front and/or back view thereof.

FIG. 5 is a bottom view thereof.

FIG. 6 is a bottom perspective view thereof.

FIG. 7 is a side view of an embodiment thereof; and,

FIG. 8 is a cut view of the embodiment of FIG. 7.

The broken lines showing the handle of the cheese slicer are for unclaimed subject matter.
